UNITED STATES PATENT OFFICE.

SAMUEL McMULLAN, OF RIVERSIDE, ILLINOIS, ASSIGNOR TO WESTERN ELECTRIC COMPANY, INCORPORATED, OF NEW YORK, N. Y., A CORPORATION OF NEW YORK.

STRAND-WORKING MECHANISM.

Application filed October 22, 1924. Serial No. 745,080.

This invention relates to improvements in strand working mechanisms, and more particularly to wire drawing machines.

An object of the invention is to provide 5 an improved mounting for the dies in a wire drawing machine, wherein each die will be positioned at a predetermined angle to the axis of the portion of the wire being drawn therethrough.

10 In accordance with one feature of the invention a wire drawing machine employing uniform diameter guide rolls cooperating with a stepped drawing element, thus causing each pass of the wire through the dies 15 to assume a different angle, is provided with a die drawing block provided with a plurality of seats for positioning drawing dies, wherein the seats are formed at predetermined and differing angles so that the axis 20 of the reducing aperture of each die placed thereon will coincide with the axis of the portion of the wire being drawn therethrough.

It is believed that the invention will be 25 clearly understood from the following description taken in connection with the accompanying drawings illustrating in one embodiment thereof each of the several features of the invention, in which

30 Fig. 1 is a front elevation, parts being broken away, showing a wire drawing machine embodying the features of the invention;

Fig. 2 is an enlarged fragmentary plan view showing the guide rolls and the die drawing block, and

35 Figs. 3 and 4 are fragmentary vertical sectional views taken on the lines 3-3 and 4-4 respectively of Fig. 2 looking in the direction indicated by the arrows, showing 40 two of the angularly disposed die seats.

Referring now to Fig. 1 of the drawings, 11 represents a framework which supports a compartment 12 of a substantially rectangular shape having top, bottom, back and side 45 walls 13, 14, 15, and 16, respectively. The front of the compartment may be closed by a suitable door or doors (not shown). The wire drawing apparatus is mounted within the compartment and comprises a horizontally disposed shaft 18 upon which is mounted a plurality of integral capstans 17-17 of different diameters. The shaft 18 is driven 50 through suitable gearing by a motor (not shown) carried by the framework and may 55

be coupled to and from the capstans through a suitable clutch mechanism. Mounted above the shaft 18 are a plurality of guide rolls 19 independently rotatable upon a horizontally disposed shaft 20 suitably supported within the compartment 12. Mounted between the sheaves 19 and the capstans 17-17 is a die drawing block 21 carried by a bracket 22 secured to the back wall of the compartment 12. The block 21 will be described in greater detail hereinafter. For a detailed illustration and description of the sheaves 19 and the driving mechanism for the capstan shaft 18, reference is made to Patent 1,598,937 to J. N. Selvig, dated September 7, 1926. The details of this construction have been omitted from the present application for the sake of simplicity, since a full description of the sheaves and driving mechanism for the capstan shaft 18 is not 70 essential to a complete understanding of the present invention.

A supply of wire 24 to be reduced in diameter is carried by a supply spool 25 mounted upright upon one end thereof at the front of 80 the machine. The spool 25 is provided with an auxiliary wire storage means. For a detailed illustration and description of the spool 25 and its auxiliary wire storage means, reference is made to applicant's co-pending application, Serial No. 164,185, filed January 28, 1927. The wire 24 is guided from the supply spool 25 over and under pulleys 26 and 27 respectively (Fig. 1) and then over the rear guide roll 19 and through 90 the first reducing die 28 carried by the die block 21. The wire is then wound once around the capstan 17 of smallest diameter, after which it is passed upward and over the next roll 19 and through the next reducing die 28 carried by the block 21. The wire 95 is then wound around the next capstan and then again over the next roll and through the next reducing die, etc., until it is fully drawn down to the desired diameter of the last reducing die. From the final reducing die the drawn wire 24 passes around the capstan 17 of largest diameter and is guided by a pulley 29 mounted on a stationary arm 31 adjustably positioned on the shaft 20. 100 From the pulley 29 the wire may pass through an opening in the closed doors (not shown) to a pulley 32 carried by an arm 33, and thence is led to a take-up spool 34 driven by suitable mechanism (not shown) and en- 110

closed by a guard 35. For a detailed illustration and description of the guard 35, reference is made to applicant's aforementioned application.

5 It will be observed by referring to Figs. 1 and 2 that the longitudinal axis of the wire 24 during its passage between the guide roll 19 and its respective capstan 17 is disposed at a widely different angle, with respect to that of the wire as it passes between the other rolls and capstans, since the guide rolls 19 are of constant diameter and the capstans 17—17 of different diameters. The die block 21 comprises a horizontally disposed body portion 36 having secured thereto shelves 37 and 38 (Figs. 3 and 4), each of which is adapted to support a series of dies 28 thereon, each die being mounted therein with the axis of its reducing aperture coincident with the axis of the wire being drawn therethrough. In the embodiment of the invention illustrated, twelve dies are mounted upon the die block, six upon each shelf thereof. The twelve dies are alternately arranged, reading from the bottom of Fig. 2, first on the lower shelf and then the upper and then the lower, etc. The first five dies distributed alternately upon the two shelves, reading from the bottom of Fig. 2, are each mounted upon a surface 40 formed at a different and definite angle, all inclined toward the right as viewed in Figs. 1, 2, and 4. The sixth die is carried upon the upper shelf 37 and is mounted upon a horizontally disposed surface 41 formed thereon. The next six dies are also distributed alternately upon the two shelves, each being mounted upon a surface 42 formed at a different and definite angle, all inclined toward the left as viewed in Figs. 1, 2, and 3. By providing the mounting just described for the drawing dies in a wire drawing machine wherein each die is positioned with the axis of its reducing aperture coincident with the axis of the wire being drawn therethrough, it will be apparent that the wear upon the die will be substantially uniform around the reducing surface of the die and that consequently the finished wire will be drawn to the desired size and contour. Also, due to the uniform positioning of all of the dies, with respect to the wire, each die being positioned with the axis of its reducing aperture coincident with the axis of each pass of the wire therethrough, the tension on the wire is more evenly distributed, thereby minimizing the stopping of the machine due to breaks in the wire during the drawing operation, which breaks might occur if the dies were not mounted with their axes coincident with the axes of the portions of the wire being drawn therethrough.

What is claimed is:

1. In a wire drawing machine, a series of dies, a mounting therefor, means for draw-

ing the wire through the dies and for causing each pass of the wire therethrough to assume a different angle from that assumed by the other passes, and means for positioning each die in the mounting at a different angle, depending upon the angle at which the wire is drawn therethrough. 70

2. In a wire drawing machine, a series of dies, a mounting therefor, means for drawing the wire through the dies and for causing each pass of the wire therethrough to assume a different angle from the horizontal, and means for positioning each die differently in the mounting with the axis of its reducing aperture coincident with the axis of the wire being drawn vertically therethrough. 75 80

3. In a wire drawing machine, a series of uniform diameter guide rolls, a stepped capstan positioned with each step thereof in line with one of said guide rolls which results in the wire passing between the guide rolls and capstan assuming different angles, a die located between each step of the capstan and one of the guide rolls, and means for mounting said die in accordance with the particular angle assumed by the wire whereby the axis of its reducing aperture coincident with the axis of the wire being drawn therethrough. 90

4. In a wire drawing machine, a series of uniform diameter guide rolls, a stepped capstan positioned with each step thereof in line with one of said guide rolls, a series of dies, and a die block for supporting said dies located between said guide rolls and stepped capstan, said die block provided with a series of die supporting surfaces, each disposed at such an angle that each die will be mounted with the axis of its reducing aperture coincident with the axis of the wire being drawn vertically therethrough. 100 105

5. In a wire drawing machine, a series of uniform diameter guide rolls, a stepped capstan positioned therebelow with each step thereof in line with one of said guide rolls, the axes of said guide rolls and capstan being disposed in substantially the same vertical plane, a series of dies, and a die block for supporting said dies located between said guide roll and stepped capstan, said die block provided with a plurality of horizontally disposed shelves, each provided with a series of die supporting surfaces, each disposed at a different angle so that the dies will be mounted with the axes of their reducing apertures in a predetermined and uniform relation to the axis of the wire being drawn vertically therethrough. 110 115 120

6. In a wire drawing machine, a series of dies, a mounting therefor, means for drawing wire through the dies and for causing each pass of the wire to assume a different angle, and means associated with said mounting and disposed at an angle different 125 130

for each die to insure the axis of the reducing aperture of the die being coincident with the axis of the wire being drawn therethrough.

5 7. In a wire drawing machine, a series of dies, means for drawing wire through the dies and for causing each pass of the wire to assume a different angle, a die block comprising a plurality of die shelves, and means

individual to the shelves inclined in opposite directions and disposed to insure the axis of the reducing aperture of each die being coincident with the axis of the wire being drawn therethrough.

In witness whereof, I hereunto subscribe my name this eighth day of October, A. D. 1924.

SAMUEL McMULLAN.
